PAUL BELYAVIN, OF LONDON, ENGLAND

INTERNAL COMBUSTION ENGINE

Application filed January 27, 1930, Serial No. 423,823, and in Great Britain January 28, 1929.

My invention relates broadly to internal combustion engines and more particularly to fuel injection valves therefor.

An object of the invention is to provide for the injection of fuel into the cylinder of an internal combustion engine and its pulverization by mechanical means without the assistance of compressed air.

Another object of the invention contemplates the provision of a fuel injection valve that is easy to install, cheap to manufacture, and efficient in operation.

In the existing fuel injection valves used at present for mechanical injection of fuel, the injection valve proper consists of a spring-loaded needle valve that is lifted off its seat by the pressure of fuel delivered to the valve by a fuel pump. With such an arrangement, any variation in the rate of fuel delivery during the injection period, however small, causes the pressure of fuel alternately either to rise or to fall, and consequently the valve does not stay open all the time, but bounces up and down, following the variation in pressure. In addition, a considerable part of the kinetic energy of fuel delivered to the valve under high pressure essential for efficient pulverization, is lost while the fuel is being withdrawn when passing through the seat of the spring-loaded valve.

To overcome these existing disadvantages of the present fuel injection valves various modified types of fuel injection devices have been introduced, some of which are provided with a spring-loaded plunger acting as an accumulator of pressure, and a valve operated by mechanical means. Injection valves of this type pulverize the fuel more efficiently and give better fuel consumption. However, their serious drawbacks are two-fold: a very complicated construction, and the necessity of having some mechanical means to operate the valve.

It is a further object of the present invention to overcome the above disadvantages by providing an accumulator plunger that is used both for maintaining a constant pressure and for operating the valve.

The invention consists essentially of a

spring-loaded plunger and a small needle valve either attached to the end of the plunger or independent thereof, and capable of movement relative to the plunger along its axis. The needle valve is kept in position by two springs acting in opposite directions to each other, one of which is alternately compressed or released by the plunger.

With the above and other objects in view the invention consists in the construction, combination, and arrangement of parts as will be described more fully hereinafter.

Reference is to be had to the accompanying drawing forming a part of this specification in which like reference characters indicate corresponding parts throughout the several views, and in which

Figure 1 is a cross sectional view through the fuel injection valve of an internal combustion engine, and

Figure 2 is a fragmentary cross sectional view of a slightly modified form of injection valve.

Referring more particularly to Figure 1 of the drawing 5 indicates a spring-loaded plunger acting as an accumulator of pressure. This accumulator plunger has reciprocal movement through a bushing or gland 6 arranged in the fuel valve body or housing 7 into which fuel is supplied under pressure through pipe 8. A needle valve 9 is mounted in a hollow end of the accumulator plunger so as to have freedom of movement therein, ports 4 being provided in the plunger 5 for admitting fuel pressure to the top of the valve 9. The needle valve is kept in position by two springs 10 and 11, each acting on the needle valve in opposite directions, whilst the pressure of the fuel acting on the upper end of the needle valve tends to keep it closed.

When the fuel pump (not shown) delivers fuel to the valve, the pressure there rises, and the accumulator plunger begins to move outward compressing spring 12, that normally holds the plunger in its innermost position keeping the needle valve on its seat. During the first part of the plunger stroke, the needle valve 9, which is acting as an injection valve proper, remains closed, and is kept on its

seat as explained. While the plunger is moving and the needle valve is still closed, spring 10, acting on the needle valve, is being gradually released, and the spring 11 more compressed. This continues until a cup shaped member 13, mounted on the inner end of the plunger, comes into contact with a shoulder 14 on the needle valve, when further movement of the plunger lifts the needle valve from its seat, and the injection of fuel through the orifices 21 begins.

The opening of the needle valve instantly releases the load thereon due to internal pressure, which will then become statically balanced, acting equally on both ends of the valve. This is true because the fuel pressure in the valve penetrates under the valve seat, thus balancing the pressure on the other end of the valve. When the needle valve is seated, the pressure of fuel in the injector presses the needle valve to its seat. This load being released, spring 11, that was compressed due to the outward movement of the accumulator plunger, instantly lifts the valve further away from its seat, thus leaving the passage for the fuel through the valve seat absolutely free, and leaving the accumulator plunger plenty of latitude to move in and out without obstructing the fuel passage by shutting the valve 9. The large spring 12 must, of course, be stronger than either of the springs 10 and 11. Injection pressure is regulated by tightening or releasing spring 12 by a nut 15 acting on washer 16 interposed between it and the spring.

When the pressure in the injection valve is released due to the delivery pump (not shown) action, the accumulator plunger drops down instantly, the adjustable washers 17 determining its final position when at rest. On its way down it presses the valve 9 on to its seat through the medium of spring 10.

The leak-off is provided through outlets 18 and 19, and 20 indicates the priming valve 48 that is mounted in the housing 7.

In the modified form illustrated in Figure 2, the needle valve 9 is not mounted in the hollow end of the plunger 5, as is the case in Figure 1, but is free to move in a guide member 22. The needle valve has an enlarged head 23 against which the upper end of spring 11 bears, the lower end of such spring 11 bearing on a shoulder on the guide member. Spring 10 bears against the outer side of the enlarged head 23 and a washer 24 encircling the reduced end of the accumulator plunger. The needle valve is kept in position by the action of springs 10 and 11, the pressure of the fuel on the upper end of the needle valve tending to keep it closed.

In this type of valve spring 11 must be sufficiently strong to lift the needle valve from its seat against the load due to internal pressure as soon as the load on spring 10 is released due to the outward movement of the

accumulator plunger. Also as in the before mentioned type, as soon as the valve 9 lifts, the load on it due to the pressure of fuel becomes balanced, and spring 11 instantly lifts the valve considerably beyond its former position, thus leaving the passage for the fuel clear.

It is to be understood that the above description and accompanying drawing comprehend but the general and preferred embodiment of my invention and that various minor changes in details of construction, proportion, and arrangement of parts may be made within the scope of the appended claims and without sacrificing any of the advantages of my invention.

Having described my invention, what I claim is:

1. In an internal combustion engine, a fuel injection valve including a pressure accumulator arranged to be reciprocated by the rise in fuel pressure, a needle valve normally held closed by said accumulator, and a spring for lifting said valve when the pressure thereon is relieved by movement of the pressure accumulator.

2. In an internal combustion engine, an injection valve for fuel including a spring-loaded plunger arranged to be reciprocated by the rise in fuel pressure having a hollow end, a needle valve mounted in said end, an expandable spring, the tension of which is adapted to be lessened by movement of the plunger, for holding the needle valve on its seat, and a spring for lifting said valve when the tension of the said first spring is lessened.

3. In an internal combustion engine, a fuel injection valve including a spring-loaded plunger arranged to be reciprocated by the rise in fuel pressure, a valve normally held closed by the plunger, and a spring operable upon the valve to open the same when the plunger is removed therefrom.

4. In an internal combustion engine, a fuel injection valve including a plunger arranged to be reciprocated by the rise in fuel pressure during the injection period and acting as an accumulator of pressure, a needle valve normally held closed by the said plunger, a spring for so holding the needle valve, and a spring for lifting the needle valve off its seat when pressure of the accumulator plunger is totally or partially removed therefrom.

5. In an internal combustion engine, a fuel injection valve including a spring loaded plunger arranged to be reciprocated by the rise in fuel pressure, a valve normally held closed by said plunger, means whereby said fuel pressure is adapted to act on the outer end of said valve, and a spring operable on said valve so that when said valve has begun to open as a result of reciprocation under pressure of said plunger and the fuel pressure loads on the valve thereby become

balanced, said valve is jumped by a quick-opening movement to full-open position by said spring.

6. In an internal combustion engine, a fuel injection valve including a pressure accumulator arranged to be reciprocated by the rise in fuel pressure, a needle valve normally held closed by said accumulator, means whereby the outer end of said valve is subjected to fuel pressure, and a spring such that when said valve has just begun to open as a result of reciprocation under pressure of said accumulator, the valve is jumped by said spring to full-open position on the balancing of the axial fuel pressure loads on the valve.

7. In an internal combustion engine, an injection valve for fuel including a spring loaded plunger arranged to be reciprocated by the rise in fuel pressure and having a hole low end, a needle valve mounted in said end, an expansible spring adapted to hold said valve on its seat and to have its tension lessened by movement of said plunger, means whereby the upper end of said valve is subjected to fuel pressure, and a spring such that whenever said valve and its seat break contact as the result of the movement of said plunger and the axial fuel pressure loads on the valve are thereby balanced, said spring causes said valve to jump to a full open position.

8. In an internal combustion engine, a fuel injection valve including a pressure accumulating plunger arranged to be reciprocated by the rise in fuel pressure, a needle valve operable thereby, means whereby the upper end of said valve is subjected to fuel pressure, a resilient member arranged between said plunger and one side of said needle valve to assist in seating said valve, and a second resilient member on the other side of said valve such that, when said plunger reciprocates under pressure, it reduces the pressure of said first resilient member on said valve, and said second resilient member thereby raises said valve out of contact with its seat, whereupon the upward fuel pressure load on said valve becomes thereby equal to the downward fuel pressure load thereon, and said second resilient member then causes said valve at once to jump to a fully open position.

9. In an internal combustion engine, a fuel injection valve including a pressure accumulating plunger arranged to be reciprocated by the rise in fuel pressure, a needle valve operable thereby, means whereby the upper end of said valve is subjected to fuel pressure, a spring arranged between said plunger and one side of said needle valve to assist in seating said valve, a second spring on the other side of said valve, and means on said plunger such that, when said plunger has been reciprocated under pressure and the pressure exerted by said first spring on said

valve has been reduced, said means comes into contact with said valve so as positively to lift said valve off its seat, whereupon the axial fuel pressure loads on the valve become balanced and said second spring causes said valve at once to jump to a fully open position.
